X-RAY APPARATUS

Alfred Kuntke, Hamburg-Wellingsbuttel, Germany, assignor to Hartford National Bank and Trust Company, Hartford, Conn., as trustee

Application September 13, 1949, Serial No. 115,408
In the Netherlands September 30, 1948

5 Claims. (Cl. 250—103)

1

This invention relates to X-ray apparatus provided with automatic control.

The maximum permissible load (number of kw.) of X-ray tubes for diagnostic purposes varies with different factors, such as the size of the focal spot, the manner in which the heat of the focal spot is withdrawn, the thermal capacity of the anode and the substance of which the anode is made. The maximum permissible load is smaller according as its duration is longer. If a given X-ray tube may be loaded for one second with a maximum power of N kw., a load of one tenth of a second duration may be, for example, 1.4 N kw. but a load of, say, 5 secs. duration must not be in excess of 0.6 N kw. The number of N may vary widely for different types of tubes; as a rule it lies between 5 and 20 but even the factors varying with time (in the said example 1.4 for 0.1 sec. and 0.6 for 5 sec.) vary considerably for the various types of tubes.

Modern X-ray apparatus comprise a control-device for the load quantities of the tube, which automatically adapts the load on the tube to the load characteristic curve, the current being adjusted as a function of the duration of loading and of the voltage across the tube, which is generally variable between 50 and 100 kv.

The requirements of the control can be better visualized with the aid of Fig. 1 and Fig. 2 of the accompanying drawings which are perspective views of three-dimensional graphs of the load capacity of an X-ray tube.

In Fig. 1, the ordinate of each point of an arculate surface ABCD is a measure of the maximum current intensity which is permissible at a voltage and for a length of time, the values of which are determined by the distances from the two vertical coordinate planes. It is desirable that with the use of the current intensity which is adjusted by the automatic control-device, the values determined by this plane should be approximated to the greatest possible extent. This is carried out in practice by using a variable resistance included in the primary circuit of the filament-supply transformer or by connecting into the circuit a voltage source which contributes to or counteracts the effect of the filament-supply transformer. The control-member of this resistance or the switches by which this voltage is connected into the circuit are coupled with the voltage control-member or with the load duration control member or with both.

As a rule, the control of the current intensity is carried out stepwise. Fig. 1 shows how in the latter case the steps may be chosen, namely in

2

three steps in accordance with the voltage chosen and in three steps in accordance with the time interval chosen, so that the current intensity may be adjusted to nine values in all.

5 The effect of the X-rays on a photographic film, that is to say the blackening of the film, is approximately proportional to $I \cdot t \cdot U^4$, where I is the intensity of the tube current, t the duration of the loading and U the voltage across the X-ray tube. The factors $I \cdot t$ (expressed in mAmps./sec.) and U (expressed in kv.) are, consequently, the quantities which determine the optimum exposure of the film.

15 In the perspective Figure 2, the product $I \cdot t$ is plotted as a function of the tube voltage U and the time interval t. In this figure the surface EFGH corresponds to the load characteristic curve of the X-ray tube. It may be seen from this figure that the stepwise control is assumed to be such that, in accordance with the shape of the surface EFGH, on an increase in time interval, the product $I \cdot t$ is not increased at the points of current variation but instead is decreased and hence also the photographic effect of the X-rays emitted by the tube. On an increase in voltage the product $I \cdot t$, at the points of current variation, falls to a lower value, so that in spite of this increase the blackening initially diminishes.

20 Apart from these deficiencies there is a further one which is due to the voltage loss occurring in the high-voltage generator and in the supply mains. Even if the automatic control were carried out completely in accordance with the surface ABCD of Fig. 1 or the surface EFGH of Fig. 2, the voltage loss in the apparatus results in a decrease in tube voltage, and this affects the blackening materially, since the latter is determined by the fourth power of U.

25 In order to transfer the load quantities of one X-ray apparatus to another it is necessary to know the tube voltages actually occurring and their correct adjustment. However, as a rule, they can be determined with the use of calibration characteristic curves only. Attempts have been made to reduce the voltage loss by keeping the internal resistance of the apparatus low. This method not only involves the use of a large amount of material and, due to the low value of the resistance, leads to breakdown of the tube if disturbances to operation occur therein, but it is inefficient when the supply mains has a high resistance.

30 It has furthermore been suggested to provide an indicating device permitting the reading of the tube voltage actually occurring, by deducting

from the value of the no-load voltage an amount which is proportional to the intensity of the tube current. The results thus obtained can only be correct so long as one is concerned with a voltage loss which is proportional with the current intensity. With a mains supply having an appreciable resistance, such as the mains supplies usually available in practice, this is not the case.

For the same reason compensation of the voltage loss by applying to the primary circuit a correction voltage which is proportional with the current does not yield satisfactory results. As may be seen from Fig. 1, this correction voltage must otherwise be chosen to vary in accordance with the voltage and time interval chosen. With any known measure of compensating or indicating the voltage loss based on the intensity of the tube current, it was invariably assumed that the resistance of the mains was negligible. In practice, however, this is not so and therefore the solutions hitherto proposed are not successful.

The present invention provides a control of improved operation which can be provided at low cost. The voltage loss is taken into account and the invention is based on recognition of the fact that at a given ratio between the resistance lying (as viewed from the mains) in front of the autotransformer controlling the voltage and that following this transformer, the voltage loss is constant throughout the voltage control-range if the load on the tube is kept constant. It has been found possible thus to compensate the voltage loss throughout the range of voltage-control by increasing the primary voltage of the high-voltage transformer by an amount varying with the load.

In order that the invention may be more clearly understood and readily carried into effect, it will now be described more fully with reference to Figures 3 to 8 of the accompanying drawings.

The principle of such voltage compensation is set out more fully hereafter.

Fig. 3 shows the greatly simplified circuit-diagram of an X-ray apparatus, in which T_1 is an autotransformer and T_2 a high-voltage transformer. U_N designates the mains voltage and R_N the resistance of the mains as far as the autotransformer, R_A designates the resistance of the autotransformer transferred to the output side and R_H the resistance of the high-voltage transformer, including that of any rectifying tubes used, transferred to the high-voltage side of the said transformer.

$X_A = U_1/U_N$ represents the ratio of the autotransformer and $X_H = U_2/U_1$ the ratio of the high-voltage transformer.

The total resistance of the circuit appearing at the high-voltage side of the transformer T_2 is calculated as follows:

$$\Sigma R = R_H + R_A \cdot X^2_H + R_N \cdot X^2_A \cdot X^2_H$$

If ΣR is plotted as a function of U_1 or U_2 , this gives the sum of a constant component

$$R_H + R_A \cdot X^2_H$$

and a quadratic component $R_N \cdot X^2_A \cdot X^2_H$, as shown in Fig. 4a.

Fig. 4a shows the control-range which extends, for example, from 50 to 100 kv. for U_2 and in which the voltage loss is required to be constant at a definite load (kw.). The limit values of this range are I and II. Since the load is required to be constant, the current intensity varies in this range by a factor 2, as indicated in Fig. 4b.

In order that the voltage loss may become con-

stant throughout the control-range, the product $I \times R$ for point I must first of all be equal to that obtaining for point II. This is ensured at a definite ratio, as is found by calculation, if

$$R_H + R_A \cdot X^2_H = 15 \dots 30 \cdot 10^3 \frac{R_N}{U^2_N} \quad (1)$$

Under this condition, if the load is looked upon as the parameter, a parallel shift of the tube voltages is obtained, as is shown in Fig. 5.

Fig. 6 shows the variation of the auxiliary voltage U as a function of the load for a definite, adequately chosen mains constant which is such that most mains connections exhibit this constant or else, may be brought in accordance therewith by use of a ballast resistance. In practice the desired result may be obtained by a mains constant of, for example, $1/380^2$ (ohm/volt ^{2}) (1 ohm for a 380 volts mains and 0.33 ohm for a 220 volts mains). The characteristic impedances of the apparatus are purposely chosen to be such that the Equation 1 is fulfilled.

If these conditions are fulfilled, the voltage loss can be compensated in a simple manner. Since the load on the X-ray tube is required to vary with the duration of the load, it is only necessary to couple the time adjusting member with a corresponding member for controlling the auxiliary voltage. This may be seen from Fig. 6. By way of example, the load N_k at the minimum time of loading to be chosen is such that for compensating the voltage loss the amount dU_k must be added. With increase in time the load drops to that which is associated with the longest time interval and is designated N_L , at which the voltage dU_L is required to be added for compensation.

In order that the technical means for carrying out the control may be reduced in size and the load to be switched may be kept small, the compensating voltage is resolved into a constant component A and a component varying with time between $-B$ and $+B$. This is particularly advantageous if two or more tubes of different power are required to be connected to the supply device. This is set out more fully with reference to Fig. 7. It is assumed that for two tubes of different load capacity the voltage loss is required to be compensated. Without introducing a great error, the component B, which varies with time, may be kept constant and the component A or A_2 may alone be chosen to correspond to the tube which is brought into operation.

An even more simple explanation will be given to show that it is possible for the voltage loss to be kept substantially constant throughout the control-range. The resistance in front of the autotransformer is assumed to be R_1 the mains resistance being consequently included and the whole of the resistance following this transformer, reduced to the primary side of the high-voltage transformer, to be R_2 . If the mains voltage is furthermore designated by E and the secondary voltage of the control-transformer by E_2 , and the primary and secondary current intensities of the control transformer I_1 and I_2 , respectively, the total voltage loss dE_2 can be assumed to be approximately equal to

$$I_1 R_1 E_2 / E_1 + I_2 R_2$$

At a definite power $N = E_1 I_1 = E_2 I_2$, we then have

$$dE_2 = N R_1 / E_1^2 \cdot E_2 + N R_2 / E_2 = N R_1 / E_1^2 (E_2 + a/E_2)$$

where $a = E_1^2 \cdot R_2 / R_1$.

When E_2 is varied between $E_{\min}$ and $E_{\max}$, $E_2 + a/E_2$ will be substantially constant, if $a = E_{\min}E_{\max}$, and consequently if

$$R_2/R_1 = E_{\min}E_{\max}/E_1^2 \quad (2)$$

Not only for $E_{\min}$ but also for $E_{\max}$ the voltage loss $dE_2 = NR_1/E_1^2(E_{\min} + E_{\max})$. Between $E_{\min}$ and $E_{\max}$, at $E_2 = \sqrt{E_{\min}E_{\max}}$, dE_2 has a minimum value of $NR_1/E_1^2 \cdot 2\sqrt{E_{\min}E_{\max}}$.

For the case considered above that $E_{\min} = \frac{1}{2}E_{\max}$ (control between 50 and 100 kv.) the ratio between the maximum and minimum values of dE_2 is $3:2\sqrt{2}$. Consequently there is only a difference of 7% between these values. The factor 15 . . . $30 \cdot 10^8$ which appears in Formula 1 is substituted for $E_{\min} \times E_{\max}$ in Formula 2. If the tube voltage is varied from 50 to 100 kv., maximum value, which corresponds with 35 to 70 kv. eff., $E_{\min} \times E_{\max} = 25 \times 10^8$. Between 45 and 90 kv. this becomes 20×10^8 .

By way of example, a simplified circuit-diagram of an X-ray apparatus according to the invention is shown in Fig. 8, it being assumed that this apparatus comprises two tubes of different load capacity.

Firstly provision must be made that the tube current as a function of the loading time and of the tube voltage exhibits a variation as represented, for example, in Fig. 1 by the surface ABCD. For this purpose both the shaft 1 for voltage-control and the shaft 2 for time control are provided with variable resistances 3 and 4, the variation of which is chosen so as to fulfill this condition.

Furthermore a variable resistance 5 acts to connect into the filament-supply circuit a resistance suitable for each of the two tubes. The filament-supply current for each of the X-ray tubes 17 and 18 is supplied from the filament-supply transformer 19. The latter is fed in a conventional manner through a voltage stabilizing device 6 from an autotransformer 7. It is efficient to load the two tubes (and any further tube that may be provided) in accordance with geometrically identical characteristic curves, which is to be understood to mean that with both tubes the tube current is controlled by the automatic device such that at each loading time the ratio between the loads (kw.) remains constant. This is advantageous since it permits of the product I_{xt} (mAmp.sec.) being indicated on a single logarithmic scale. Differences in load capacity between the tubes are allowed for by shifting the scale or the pointer through a distance the value of which varies with the ratio between the loads.

The autotransformer 7 is connected to the mains 8. A resistance 9 serves to adjust the mains resistance to the desired value. A controller 10 has the function of supplying the correct voltage to the autotransformer in the event of voltage fluctuations in the mains. The correct voltage may be read from a voltmeter 11.

The high-voltage generator comprises a transformer 12, the secondary alternating current of which is converted into direct current by rectifying tubes 13 and supplied at will through arms 14 and 15 of a switch to either of the two X-ray tubes 17 and 18.

The auxiliary voltage dU for compensating the voltage loss is added as follows: The component A is taken directly from an auxiliary winding 20, which is provided on the control transformer. The component B is taken from a winding 22

with the use of a control-member 21, which is coupled to the time selector. The winding 22 is connected to the control-transformer. The component B is added through a transformer 23 to the voltage which acts on the primary winding of the high-voltage transformer 12. The current is switched on and off by an electromagnetically controlled switch 24, the energizing current of which is controlled by a time switch 25.

10. What I claim is:

1. A circuit arrangement for energizing an X-ray tube with automatic control of tube current comprising a low-tension circuit for energizing the cathode of the X-ray tube including means to adjust the loading time of the tube for a predetermined time interval, a separate high-tension circuit having a given electrical resistance for energizing the anode of the X-ray tube, means to couple the high- and low-tension circuits to a source of electrical power having an electrical resistance proportional to the electrical resistance of the high-tension circuit for which the voltage loss across the tube is proportional to the input power to the tube, and means included in the high-tension circuit for compensating for the voltage loss resulting with current flow in the high-tension circuit and from the source comprising means to derive a relatively constant voltage component proportional to the voltage applied from the source, means to add the voltage thus derived to the voltage applied from the source to the high-tension circuit, means to derive a voltage proportional to the adjusted loading time of the tube, and means to add the voltage proportional to the adjusted loading time to the sum of the applied voltage and the voltage proportional to the applied voltage to thereby adjust the voltage applied to the tube to the equivalent no-load voltage without compensation.

2. A circuit arrangement for energizing an X-ray tube with automatic control of tube current comprising a low-tension circuit for energizing the cathode of the X-ray tube including means to adjust the loading time of the tube for a predetermined time interval, a separate high-tension circuit including a high-tension transformer and having a given electrical resistance for energizing the anode of the X-ray tube, means to couple the high- and low-tension circuits to a source of electrical power having a given electrical resistance proportional to the electrical resistance of the high-tension circuit for which the voltage loss across the tube is proportional to the input power to the tube, and means included in the high-tension circuit for compensating for the voltage loss resulting with current flow in the high-tension circuit and from the source comprising means to derive a relatively constant voltage component proportional to the voltage applied from the source, means to add the voltage thus derived to the voltage applied from the source to the high-tension circuit, an adjustable inductor responsive to the adjustment of said tube timing means coupled to the source of electrical power for deriving a voltage proportional to the adjusted loading time of the tube, and means to add the voltage proportional to the adjusted loading time to the sum of the applied voltage and the voltage proportional to the applied voltage to thereby adjust the voltage applied to the tube to the equivalent no-load voltage without compensation.

3. A circuit arrangement for energizing an X-ray tube with automatic control of tube cur-

rent comprising a low-tension circuit for energizing the cathode of the X-ray tube including means to adjust the loading time of the tube for a predetermined time interval, a separate high-tension supply circuit having a given electrical resistance for energizing the anode of the X-ray tube, a common transformer for coupling the high- and low-tension circuits to a source of electrical power having an electrical resistance proportional to the electrical resistance of the high-tension circuit for which the voltage loss across the tube is proportional to the input power to the tube, and means included in the high-tension circuit for compensating for the voltage loss resulting with current flow in the high-tension circuit and from the source comprising a transformer winding coupled to said common transformer for deriving a relatively constant voltage component proportional to the voltage applied from the source through said common transformer in series with said high-tension supply circuit, an adjustable inductor responsive to the adjustment of said tube timing means coupled to said common transformer for deriving a voltage proportional to the adjusted loading time of the tube, and a control transformer in the high-tension supply for adding the voltage proportional to the adjusted loading time to the sum of the applied voltage and the voltage proportional to the applied voltage to thereby adjust the voltage applied to the tube to the equivalent no-load voltage without compensation.

4. A circuit arrangement for energizing an X-ray tube with automatic control of tube current comprising a low-tension circuit for energizing the cathode of the X-ray tube including means to adjust the loading time of the tube for a predetermined time interval, a separate high-tension circuit having a given electrical resistance for energizing the anode of the X-ray tube, means to couple the high- and low-tension circuits to a source of electrical power including an electrical resistance for adjusting the resistance of said source to a value proportional to the electrical resistance of the high-tension circuit for which the voltage loss across the tube is proportional to the input power to the tube, and means included in the high-tension circuit for compensating for the voltage loss resulting with current flow in the high-tension circuit and from the source comprising means to derive a relatively constant voltage component proportional to the voltage applied from the source, means to add the voltage thus derived to the voltage applied from the source to the high-tension circuit, means to derive a voltage proportional to the adjusted loading time of the

5 tube, and means to add the voltage proportional to the adjusted loading time to the sum of the applied voltage and the voltage proportional to the applied voltage to thereby adjust the voltage applied to the tube to the equivalent no-load voltage without compensation.

5. A circuit arrangement for energizing an X-ray tube with automatic control of tube current comprising a low-tension circuit for energizing the cathode of the X-ray tube including means to adjust the loading time of the tube for a predetermined time interval and means to control the current to the cathode proportional to the adjusted voltage applied to the tube, a separate high-tension circuit having a given electrical resistance for energizing the anode of the X-ray tube, means to couple the high- and low-tension circuits to a source of electrical power including an electrical resistance for adjusting the resistance of said source to a value proportional to the electrical resistance of the high-tension circuit for which the voltage loss across the tube is proportional to the input power to the tube, and means included in the high-tension circuit for compensating for the voltage loss resulting with current flow in the high-tension circuit and from the source comprising means to derive a relatively constant voltage component proportional to the voltage applied from the source, means to add the voltage thus derived to the voltage applied from the source to the high-tension circuit, means to derive a voltage proportional to the adjusted loading time of the tube, and means to add the voltage proportional to the adjusted loading time to the sum of the applied voltage and the voltage proportional to the applied voltage to thereby adjust the voltage applied to the tube to the equivalent no-load voltage without compensation.
